UNITED STATES PATENT OFFICE.

CHARLES M. BULLER, OF MILWAUKEE, WISCONSIN, ASSIGNOR TO L. J. MUELLER FURNACE COMPANY, OF MILWAUKEE, WISCONSIN, A CORPORATION OF WISCONSIN.

DOUBLE-WALL PIPE.

1,300,115.

Specification of Letters Patent. Patented Apr. 8, 1919.

Application filed September 25, 1918. Serial No. 255,715.

To all whom it may concern:

Be it known that I, CHARLES M. BULLER, a citizen of the United States, and resident of Milwaukee, in the county of Milwaukee and State of Wisconsin, have invented new and useful Improvements in Double-Wall Pipes, of which the following is a description, reference being had to the accompanying drawings, which are a part of this specification.

This invention relates to improvements in hot air pipes more particularly adapted for furnace use.

Furnace pipes of the modern type are usually formed of double wall construction and in sections of a length convenient to cut from the sheet metal and to handle and assemble. The two walls are spaced apart to form an insulating air space therebetween to increase the heat conductivity of the inner pipe and prevent waste of heat. Pipe sections of this type are usually factory made and provided with overlapping interlocking joints and are jointed together at the place of installation to form pipes of the proper length. As the lengths of pipe desired for the different installations vary in length it is desirable to provide means for adjusting the length of one of the sections of pipe to provide the desired length of the assembled sections without interfering with the convenient manner of assembling the sections together.

It is one of the objects of the present invention to provide a double wall pipe which has the before-mentioned desirable features and which is of inexpensive and efficient construction.

A further object of the invention is to provide a double wall pipe having sections which may be easily superposed above another section through the medium of an improved joint to permit the sections to be adjustably connected together.

A further object of the invention is to provide a double wall pipe having a joint construction which will permit the trimming of one of the ends of one of the sections to adjust the length of the assembled sections to a predetermined height.

A further object of the invention is to provide a double wall pipe in which the corner portions are constructed in a manner to reinforce the parts.

A further object of the invention is to provide a double wall pipe which is of simple construction, is strong and durable and is well adapted for the purpose described.

With the above and other objects in view the invention consists of the improved double wall pipe and its parts and combinations as set forth in the claims, and all equivalents thereof.

In the accompanying drawing in which the same reference characters indicate the same parts in all of the views:

Figure 1 is a side view of a plurality of sections of the improved double wall pipe, parts being shown in section;

Fig. 2 is a vertical sectional detail view, on a larger scale, taken on line 2-2 of Fig. 1; and

Fig. 3 is a transverse sectional view taken on line 3-3 of Fig. 1.

Referring to the drawing, the numerals 5 and 6 indicate two of the pipe sections which are constructed in a novel manner to provide the improved adjustable joint 7 to be later described. Each pipe section is of rectangular form in cross section and consists of an inner wall 8 and an outer wall 9 connected together in spaced relation to form an insulating air space 10 between said walls. Said inner and outer walls are formed of pieces of sheet metal joined together along their vertical edge portions to form the corner edges of the pipe by interlocking lapped joints 8' and 9' which provide for the convenient manufacture of the sections and materially increase the strength of said sections. The lower end portions of the inner walls 8 of the section 5 are bent inwardly to form stop shoulders 11 and are then bent outwardly in a series of angles 12 to join the inner and outer walls together as indicated by the numeral 13. The opposite end portions of the said connected together ends 13 are bent inwardly to form locking shoulders 14 which are adapted to snap over co-acting shoulders 15 formed on the upper end of the section 5' by inclining the outer wall inwardly in a series of angles 16 to connect the upper end portions of said walls together. The co-acting shoulders 15 at the opposite side portions of the pipe serve as guide and spacing portions for the overlapping lower end portions of the pipe section placed thereon. The connecting por-

100
105

tions 16 of the outer wall are also bent outwardly to form outer stop shoulders 17. The outer stop shoulders 17 are engaged by the lower end portions of the outer walls of the 5 upper pipe section placed thereon, and the inner stop shoulders 11 are engaged by the upper end portions of the inner walls of a lower pipe section upon which the upper section is placed. The angular inwardly and 10 outwardly bent connecting portions 12 and 16 are provided with apertures 12' and 16' to permit air circulation therethrough.

The upper portions of the pipe section 5 are similar to the upper portions of the pipe 15 section 5' with the exception that instead of the inwardly bent portions 16 of the outer wall directly engaging the inner wall, independent U-shaped spacing members 18 are interposed between the two walls and the 20 upper edges of said members 18 are bent over to form overlapping engagements with the upper edges of the inner and outer walls. Said U-shaped spacing members form elongated grooves or recesses 19 for receiving 25 the lower end portions of the inner wall 8 of the adjustable upper section 6. The lower end portions of the inner and the outer walls of the upper section 6 extend downwardly in straight lines and are not attached 30 to each other so that the inner wall portions 8 can be inserted into the grooves 19 and the outer wall portions 9 can overlap or telescope the angular inwardly bent portions 16 of the outer wall 9 of the section 5. The 35 inner wall 8 of the section 6 projects below the outer wall 9 to conveniently expose to view the inner walls of both sections while slipping said inner walls together. The straight lower portions of the inner and 40 outer walls and the projection of the inner wall below the outer wall also provides for conveniently cutting or trimming both lower edge portions to secure the desired height of the combined sections.

45 It will also be noted that the inner upper edge portions 18' of the U-shaped spacing member project above the outer portions of said member, to provide for the more conveniently inserting of the lower edge portions 50 of the inner wall into the groove or recess 19 of said member.

The upper end portion of the section 6 is similar to the upper end portion of the section 5' to provide for engagement with a 55 register box.

In use the various standard sections are joined and locked together and the upper adjustable section is trimmed along its lower edge portions the desired extent to form the 60 total height desired when the parts are all assembled thus providing for utilizing sections of a standard size in fitting installations which vary in length or height over multiples of the sections.

65 From the foregoing description it will be

seen that the double wall pipe is of very simple construction and is well adapted for the purpose desired.

What I claim as my invention is:

1. A double wall pipe, comprising a section of double wall pipe having one of its end portions formed with elongated recesses, and another section of double wall pipe having an outer wall which telescopes over the outer wall of the first mentioned section and 70 having an inner wall which enters the elongated recesses thereof, said outer and inner walls of the second mentioned section adapted to be trimmed at one end to vary the combined length of the sections when assembled together.

2. A double wall pipe, comprising a section of double wall pipe having its inner and outer walls connected together at one end and forming elongated recesses therebetween, and another section of double wall pipe having portions of the inner and outer walls at one end disconnected, said last mentioned outer wall telescoping over the outer 80 wall of the first mentioned section and having an inner wall which enters the elongated recesses, said outer and inner walls of the second mentioned section adapted to be trimmed at one end to vary the combined length of the sections when assembled together.

3. A double wall pipe, comprising a section of double wall pipe having spacing members connecting the inner and outer walls together at one end and forming elongated recesses between said walls, and another section of double wall pipe having portions of the inner and outer walls at one end disconnected and one of the portions projecting beyond the other, said last mentioned outer wall telescoping over the outer wall of the first mentioned section and having an inner wall which enters the elongated recesses, said outer and inner walls of the second mentioned section adapted to be trimmed at one end to vary the combined length of the sections when assembled together.

4. A double wall pipe, comprising a section of double wall pipe having U-shaped spacing members connecting the inner and outer walls at one end and forming elongated recesses between said walls, and another section of double wall pipe having portions of the inner and outer walls at one end disconnected and the inner wall projecting beyond the outer wall, said last mentioned outer wall telescoping over the outer wall of the first mentioned section and said projecting inner wall portion entering the elongated recesses, said outer wall and the projecting inner wall of the second mentioned section adapted to be trimmed at one end to vary the combined length of the sections when assembled together.

5. A double wall pipe, comprising a section of double wall pipe having U-shaped spacing portions connecting the inner and outer walls at one end and forming elongated recesses between said walls, one of the walls forming each of said recesses projecting beyond the outer walls, and another section of double wall pipe having portions of the inner and outer walls at one end disconnected and the inner wall projecting beyond the outer wall, said last mentioned outer wall telescoping over the outer wall of the first mentioned section and said projecting inner wall portion entering the elongated recesses, said outer and the projecting inner walls of the second mentioned section adapted to be trimmed at one end to vary the combined length of the sections when assembled together.
- 10 6. A double wall pipe, comprising a section of double wall pipe having the outer wall portions inclined inwardly in a series of
- 15 angles toward the inner wall portions and forming stop shoulders, U-shaped spacing members interposed between the inner wall portions and the inclined portions of the outer wall and connected thereto and forming elongated recesses between said walls, and another section of double wall pipe having portions of the inner and outer walls at one end disconnected and the inner wall projecting beyond the outer wall, said outer wall telescoping over the inwardly inclined portions of the outer wall of the first mentioned section and said projecting inner wall portion entering the elongated recesses, said outer and the projecting inner walls of the second mentioned section adapted to be trimmed at one end to vary the combined length of the sections when assembled together.
- 20

In testimony whereof, I affix my signature.

CHARLES M. BULLER.
